[57] CLAIM

The ornamental design for an open frame coaster vehicle, as shown and described.

DESCRIPTION

FIG. 1 is a side elevational view of an open frame coaster vehicle, showing my new design the opposite side being substantially a mirror image thereof;
FIG. 2 is a top plan view thereof;
FIG. 3 is a bottom plan view thereof;
FIG. 4 is a front elevation view thereof; and
FIG. 5 is a rear elevational view thereof.
